UNITED STATES PATENT OFFICE

149,776

DESIGN FOR A HAND DRILL OR SIMILAR ARTICLE

John W. Rundt, Canton, Ohio

Application December 11, 1946, Serial No. 135,404

Term of patent 14 years

(Cl. D54—4)

To all whom it may concern:

Be it known that I, John W. Rundt, a citizen of the United States, residing at Canton, in the county of Stark and State of Ohio, have invented a new, original, and ornamental Design for a Hand Drill or Similar Article, of which the following is a specification, reference being had to the accompanying drawing, forming part thereof.

Figure 1 is a perspective view of a hand drill, showing my new design;

Fig. 2 is a plan elevational view thereof; and

Fig. 3 is a rear elevational view thereof.

The dominant features of my design reside in the portions shown in full lines.

I claim:

The ornamental design for a hand drill or similar article, substantially as shown and described.

JOHN W. RUNDT.
